LOOM LET-OFF MECHANISM

Oscar V. Payne, Leicester, Mass., assignor to Crompton & Knowles Loom Works, Worcester, Mass., a corporation of Massachusetts

Application October 3, 1934, Serial No. 746,696

10 Claims. (Cl. 139—100)

This invention relates to looms for weaving textile fabrics and more particularly to the let-off mechanism used in such looms. Such let-off mechanism is provided to control the unwinding 5 of the warp beam and to tension the warp threads during the weaving operation.

A let-off mechanism for such purposes is shown in my prior Patent No. 1,803,143, issued April 23, 1931. It is the general object of my present invention to improve and simplify the construction shown in said prior patent, and to provide an improved let-off mechanism which may be economically manufactured and which will be effective and reliable in use.

15 My invention further relates to arrangements and combinations of parts which will be herein-after described and more particularly pointed out in the appended claims.

A preferred form of my invention is shown in 20 the drawings, in which

Fig. 1 is a side elevation of parts of a loom embodying my invention;

Fig. 2 is a partial plan view of the let-off mechanism, taken along the line 2—2 in Fig. 1;

25 Fig. 3 is an enlarged end elevation, looking in the direction of the arrow 3 in Fig. 2;

Fig. 4 is a sectional plan view, taken along the line 4—4 in Fig. 3;

30 Fig. 5 is a partial end elevation, with certain parts broken away;

Fig. 6 is a sectional plan view, taken along the line 6—6 in Fig. 5;

Figs. 7, 8, 9 and 10 are front views of separate 35 elements of a friction clutch;

Fig. 11 is a rear elevation, partly in section, looking in the direction of the arrow 11 in Fig. 1, and

Fig. 12 is a detail sectional plan view, taken along the line 12—12 in Fig. 11.

40 Referring to the drawings, I have shown portions of a loom frame 10 having supports or bearings 11 for a warp beam 12. The warp W is drawn from the warp beam 12 around a guide-roll 13 and is drawn forward through the harnesses 14 in the usual manner.

45 A gear 15 (Figs. 3 and 4) is mounted on the gudgeon 16 of the warp beam 12 and is provided with a cap 17 (Fig. 3) and bolts 18 by which it may be secured in place. Lugs 20 (Figs. 3 and 50 4) on the web 25 of the gear 15 engage opposite sides of a projection 21 on the hub of the warp beam 12, whereby a positive driving connection is insured between the gear 15 and warp beam 12.

55 A gear casing 22 is mounted on and supported by the gear 15 and is preferably formed in two parts secured together by bolts 23. The casing 22 is provided with bearing surfaces 24 at each side of the web 25 of the gear 15, and is also provided with external annular bearing surfaces 60 26 engaging corresponding internal annular bear-

ing surfaces 27 on the gear 15. By such engagement the casing 22 is accurately centered and firmly positioned, while at the same time permitting relative rotation of the gear.

An elongated pinion 30 (Fig. 4) is loosely 5 mounted on a stud 31 which is slideable but non-rotatable in bearings 32 and 33. A plate 35 (Figs. 6 and 10) is mounted with a drive fit on the stud 31 and is provided with lugs 36 adapted to be positioned in recesses 37 (Fig. 5) in a 10 forwardly enlarged portion 38 of the casing 22. The plate 35 and stud 31 are thus held from rotation.

A friction ring 40 (Fig. 8) of cork or other 15 suitable material is mounted adjacent the plate 35 and a disc 42 is mounted adjacent the friction ring 40. The disc 42 has its central portion formed to fit loosely around and between the teeth of the pinion 30, as shown in Fig. 5, while its exterior diameter is such that it clears the 20 inner face of the casing portion 38.

A second friction ring 40a is mounted at the 25 opposite side of the disc 42, and a non-rotatable plate 44 is mounted adjacent the friction disc 40a. The plate 44 has an interior opening 45 of sufficient size to clear the pinion 30 and is provided with lugs 46 loosely fitting in the casing recesses 37 previously described.

Additional members 40, 42 and 44 may be assembled as indicated in Fig. 6 to form a friction 30 clutch having any desired number of plates.

A lever 50 (Fig. 3) is pivoted on a stud 51 mounted in bearing projections 52 on the cover 53 of the casing portion 38. A coil spring 55 (Fig. 11) is interposed between the lever 50 and the casing 22 and acts to force the contact end 56 (Fig. 4) of the lever 50 against the outer end of the stud 31, thus applying pressure to the friction clutch members and normally preventing 35 rotation of the pinion 30 and gear 15, relative to the casing 22.

The lever 50 is provided with a cam-shaped 40 end portion 57 positioned for engagement with a stud 58 (Fig. 1) depending from a bracket 59 secured in fixed position on the loom frame 10.

45 A counterweight 60 is suspended by a chain 61 from a stud 62 (Fig. 11) which extends across a suitable guide groove 63 in the periphery of the casing 22. As the lever 50 normally applies pressure through the friction clutch to prevent rotation of the pinion 30, the weight W normally 50 acts through the casing 22, pinion 30 and gear 15 to apply tension to the warp beam 12 and to resist rotation thereof.

55 As the warp W is gradually taken up by the loom, however, the warp beam is slowly advanced and the weight 60 is gradually lifted. When the warp beam has advanced to a position where the cam portion 57 of the lever 50 engages the fixed 60 stud 58, the stud 58 moves the lever 50 against

the pressure of the spring 55 and releases the pressure on the friction clutch which has held the pinion 30 from rotation.

5 The pinion 30 and casing 22 and all parts associated therewith thereupon move counter-clockwise (as viewed in Figs. 1 and 3) until the cam portion 57 is disengaged from the stud 58, and until the spring 55 again applies pressure to the friction clutch. In this way the weight 10 60 is maintained in operative position, regardless of the continued gradual rotation of the warp beam 12 and the gear 15.

15 It is sometimes necessary to manually adjust the position of the weight 60, particularly when starting a new warp beam, and for this purpose I provide additional mechanism best shown in Figs. 11 and 12.

20 This mechanism comprises a pinion 70 fixed to a shaft 71 having bearings in the casing 22 and extending forwardly therefrom. A recess 72 is provided in the casing 22 to receive the pinion 70 and also to receive a coil spring 73 by which the pinion is normally forced forward to a position where it is out of engagement with the gear 15. 25 A hand wheel 75 is secured to the forward end of the shaft 71 and affords means by which the pinion 70 may be manually rotated.

30 A flange or collar 76 is also provided on the outer end of the shaft 71, which part engages an offset lug 77 (Figs. 11 and 3) formed at the end of a laterally projecting portion 78 of the lever 50.

35 When it is desired to adjust the weight 60 manually, the hand wheel 75 is pushed in, which movement first causes the pinion 70 to engage the gear 15, and then causes the flange or collar 76 to engage the lug 77 and release the friction clutch. The operator is then free to turn the hand wheel and raise or lower the weight 60 as desired.

40 From the foregoing description it will be seen that my improved let-off mechanism comprises relatively few and simple parts and that it is almost impossible for these parts to fail to operate when and as intended.

45 Having thus described my invention and the advantages thereof, I do not wish to be limited to the details herein disclosed, otherwise than as set forth in the claims, but what I claim is:—

50 1. In a loom having a warp beam, a let-off mechanism comprising a warp beam gear, a pinion meshing therewith, friction means to hold said pinion from rotation, and means rendered operative by continued rotation of the warp beam to temporarily disable said friction means and thereby permit rotation of said pinion.

55 2. In a loom having a warp beam, a let-off mechanism comprising a warp beam gear, a pinion meshing therewith, a friction clutch to hold said pinion from rotation, and means rendered operative by continued rotation of the warp beam to temporarily disable said friction clutch and thereby permit rotation of said pinion.

60 3. In a loom having a warp beam, a let-off mechanism comprising a warp beam gear, a pinion meshing therewith, friction means to hold said pinion from rotation, a casing for said gear in which said pinion is mounted, a weight suspended from said casing, friction means effective to normally hold said pinion from rotation in said casing, thereby preventing relative movement of said gear and casing, and means rendered operative by continued rotation of the warp beam to temporarily disable said friction means and thereby permit rotation of said pinion.

65 4. In a loom having a warp beam, a let-off

mechanism comprising a warp beam gear, a pinion meshing therewith, friction means to hold said pinion from rotation, a casing for said gear in which said pinion is mounted, a weight suspended from said casing, a friction clutch for said pinion, a spring actuated lever rendering said friction clutch normally operative, and means to engage said lever and release said friction clutch on continued rotation of the warp beam, thereby permitting rotation of said pinion.

5

10

5 In a loom having a warp beam, a let-off mechanism comprising a warp beam gear, a pinion meshing therewith, friction means to hold said pinion from rotation, a casing for said gear in which said pinion is mounted, a weight suspended from said casing, a friction clutch for said pinion, a spring-actuated lever rendering said friction clutch normally operative, and means to engage said lever and release said friction clutch, said latter means being rendered temporarily operative by the unwinding movement of said warp beam.

15

6 In a loom having a warp beam, a let-off mechanism comprising a warp beam gear, a pinion meshing therewith, friction means to hold said pinion from rotation, means rendered operative by continued rotation of the warp beam to temporarily disable said friction means and thereby permit rotation of said pinion, and additional means to rotate said pinion manually.

20

7 In a loom having a warp beam, a let-off mechanism comprising a warp beam gear, a pinion meshing therewith, friction means to hold said pinion from rotation, means rendered operative by continued rotation of the warp beam to temporarily disable said friction means and thereby permit rotation of said pinion, and additional means to rotate said pinion manually and to simultaneously disable said friction means.

25

8 In a loom having a warp beam, a let-off mechanism comprising a warp beam gear, a pinion meshing therewith, friction means to hold said pinion from rotation, a casing for said gear in which said pinion is mounted, a weight suspended from said casing, a friction clutch for said pinion, a spring-actuated lever rendering said friction clutch normally operative, means to engage said lever and release said friction clutch on continued rotation of the warp beam, an axially slidabile pinion and hand wheel yieldingly held in normal inoperative position, and a connection between said additional pinion and said lever, whereby movement of said additional pinion to operative position will effect release of said friction clutch.

30

9 In a loom having a warp beam, a let-off mechanism comprising a warp beam gear, a pinion meshing therewith, friction means to hold said pinion from rotation, a device operative to render said friction means normally operative, and means to temporarily disable said device.

35

10 In a loom having a warp beam, a let-off mechanism comprising a warp beam gear, a pinion meshing therewith, friction means to hold said pinion from rotation, a lever, a spring engaging said lever and effective to render said friction means normally operative, said lever having a cam portion, and a fixed abutment engaged by said cam portion as said warp beam is advanced, said lever being temporarily moved to a position in which said friction means is inoperative by such engagement.
